[57] CLAIM

The ornamental design for a faceted roof dome, substantially as shown and described.

DESCRIPTION

FIG. 1 is a top perspective view of a faceted roof dome showing my new design;

FIG. 2 is a top plan view thereof;

FIG. 3 is a front elevational view thereof, it being understood that the rear and left and right views are identical thereto; and

FIG. 4 is a bottom plan view thereof.

Fig. 2.

Fig. 3.

Fig. 4.
